US00D660647S

(12) **United States Design Patent**
Casey et al.

(10) **Patent No.:** US D660,647 S
(45) **Date of Patent:** ** May 29, 2012

(54) **OVEN RACK**

(75) Inventors: **Warren Casey**, Georgetown, IN (US);
Ted Henderson, Hartford, WI (US);
Tom Stollenwerk, Mayville, WI (US);
Jan Bartelick, Germantown, WI (US)

(73) Assignee: **Alto-Shaam, Inc.**, Menomonee Falls, WI (US)

(**) Term: **14 Years**

(21) Appl. No.: **29/407,460**

(22) Filed: **Nov. 29, 2011**

(51) **LOC (9) Cl.** 07-02

(52) **U.S. Cl.** D7/408

(58) **Field of Classification Search** D6/462–463, D6/513, 566, 323; D7/323, 329–332, 337, D7/339, 346–347, 354–363, 387, 391, 393, D7/395, 402, 408, 409, 411, 504; D19/90; 99/324–325, 331–332, 337–340, 355, 369, 99/403–419, 425–426, 444, 450; 211/41.2, 211/57.1, 74, 85.4, 106, 181.1; 220/485, 220/491, 573.1–573.5, 759, 912
